UNITED STATES PATENT OFFICE.

GEORGE W. COLLIN, OF BRIDGEPORT, CONNECTICUT.

STEAM TRAP.

1,410,656.

Specification of Letters Patent. Patented Mar. 28, 1922.

Application filed April 28, 1920. Serial No. 377,204.

To all whom it may concern:

Be it known that I, GEORGE W. COLLIN, a citizen of the United States, and resident of Bridgeport, in the county of Fairfield and 5 State of Connecticut, have invented certain new and useful Improvements in Steam Traps, of which the following is a specification.

My invention relates to new and useful 10 improvements in steam-traps for installation in steam pipe lines, to receive and automatically discharge the condensed steam therefrom.

The invention particularly relates to ther- 15 mostatically operated steam-traps, wherein the thermostat is arranged wholly within the the valve casing and thus directly exposed to the action of the varying steam tempera- ture, and whereby the varying temperature 20 will automatically open and close the valve to relieve the trap from the water accumu- lated therein, produced by condensation.

The object of the present invention, is to 25 provide a steam-trap which will include a thermostat and valve operatively connected so that the latter will be automatically operated by the former; to support the valve and thermostat upon a detachable part which is 30 removably supported within a casing and which can be conveniently removed there- from when desired and whereby the several operative parts of the thermostat may be 35 readily gotten out for the purpose of clean- ing or repairing, and further to include as a valve carrying member, a differential lever 40 including opposed arms that contact with the thermostat at distant points so as to obtain increased leverage upon the valve for open- ing the same.

With these and other objects in view the 45 invention resides and consists in the construction and novel combination and arrangement of parts hereinafter more fully described, 50 illustrated in the accompanying drawings, and pointed out in the claims hereto app- 55 ended, it being understood that various changes in the form, proportion, size and minor details of construction within the scope of the claims may be resorted to with- 60 out departure from the spirit or sacrificing any of the advantages of the invention.

Similar characters of reference denote like 65 or corresponding parts throughout the sev- eral figures of the accompanying drawings 70 forming a part of this specification, and upon which,

Fig. 1 is a central vertical sectional view through my improved form of steam-trap, shown connected to a steam pipe line, the valve being shown slightly raised from its 60 seat.

Fig. 2 shows a central vertical sectional view of the removable closure plate and at- 65 tached outlet connection, together with the thermostat and valve lever mounted thereon,

Fig. 3 shows a sectional plan view taken on line 3—3 of Fig. 1, the free end portion of the thermostatic loop being omitted.

My improved steam-trap is designed so 70 that the main body portion thereof may be permanently attached to a pipe line, and in- 75 cludes a chamber to which the steam and water from the pipe line are admitted for the operation of the thermostat and valve 75 connected therewith. The chamber in the body is provided with a removable closure plate upon which the entire interior mecha- 80 nism is mounted and by means of which the said mechanism may be removed in a very 80 simple manner thus avoiding the incon- 85 venience of getting at the parts while in the casing.

Referring in detail to the characters of re- 85 ference marked upon the drawings, 5 repre- 90 sents a steam pipe which may be a short ex- 95 tension of a main pipe line, not shown, and through which the steam is admitted to the chamber 6 of the tubular casing 7. The lower peripheral edge portion of this cas- 90 ing is threaded to receive the holding flange 95 of the nut 8, which serves to engage and clamp the annular edge portion 9 of the closure plate 10 in position against the lower 100 annular end portion of the casing. The closure plate includes a hub having a thread- 100 ed surface of the coupling 11 serves to se- 105 curely hold it in position.

The upper end of the port 14 of this outlet 105 connection forms a valve seat which is nor- mally closed by the ball valve 15 mounted on the short arm 16 of the differential lever 17. This lever is hung upon a pivot 18 se- 110 cured between the flanges 19 of the post 20 formed on the closure plate, and is provided with two arms that are disposed substantially parallel with both the outlet port and the 110 operative end portion of the thermostat. The short end of the lever includes a right

angle extension in which is positioned an adjustable contact screw 21 for engagement with the extreme end portion of the thermostat 22. The end 23 of the lever is disposed upward on the opposite side of the end portion of the thermostat from that of the extension 16 and is also provided with an adjustable contact screw 24 which engages the opposite side of the thermostat from that engaged by the before mentioned screw 21.

The thermostat 22 is of a loop formation and has its fixed end secured to the before mentioned post 20 so that an effective movement of the free end of the thermostat is obtained against the contact points 21 and 24. The contractive action of the thermostat obviously operates upon the long lever, through its engagement with the contacting screw 24, in a way to form a greater leverage than it would if engaged closer to the pivoted point 18, better to move the ball valve from its seat, thus making the valve more sensitive to slight variations in temperature and therefore more readily operated.

The normal position of the thermostat when the trap is not in service, is to hold the valve open, and when steam enters the chamber its temperature expands the thermo-loop so that its free end will engage the contact screw 21, carrying the short arm over and seating the valve. In this connection it will also be understood that the coupling 11 bearing the valve seat may be adjusted with respect to the closed position of the valve after the trap has been installed and while the service pressure is in the chamber. With the valve closed, the condensation from the steam accumulates in the chamber and when it becomes of sufficient quantity its lower temperature will affect the thermo-loop, contract the same so that its free end will be drawn in and its side portion engage with the contact screw 24 which is positioned in the long arm of the lever in a way to obtain a greater leverage upon the valve arm, thus providing initial force sufficient to overcome the resistance of the pressure on the valve. The further operation of the thermostat, after the valve has been moved from its seat, serves to engage its lower end portion 25 with the portion 26 of the lever, near its pivotal point, in a way to more rapidly operate the same, and swing the valve entirely away from its seat.

From the foregoing it will be seen that aside from the desirable operative qualities of the thermostat and the valve lever, the device is also made especially attractive by reason of the fact that all of the said parts can readily be drawn out by simply first re-

moving the flanged nut which permits the 60 closure plate and parts mounted thereon to be withdrawn.

Having thus described my invention, what I claim and desire to secure by Letters Patent, is—

1. A steam-trap, including a chamber, a thermo-loop one end of which is secured within the chamber and the other end of which is free therein, a valve lever including opposed arms intermediate of which the free end of the thermo-loop is positioned, one of said arms contacting with the said free end portion of the thermostat farther from the pivotal point of the lever than the other.

2. A steam-trap, including a body having a chamber therein and an outlet port, a valve lever pivotedly mounted in the chamber and including a long and a short arm, a thermo-loop mounted in the chamber and having its operative end disposed between the two said arms to engage one farther from its pivotal point than the other, and a valve mounted on the short arm to close the outlet port.

3. A steam-trap, including a body having a chamber therein and an outlet port, a valve lever pivotedly mounted in the chamber and including a long and a short arm, a thermo-loop mounted in the chamber and having its operative end disposed between the two said arms and adapted to make a single engagement with one arm for closing the valve and to form a dual engagement with the other arm in the operation of opening the valve, and a valve mounted on the short arm to close the outlet port.

4. A steam-trap, including a body having a chamber therein, and an outlet port, a valve lever pivotedly mounted in the chamber and including two arms disposed parallel with the outlet port, a thermo-loop mounted in the chamber and having its operative end also disposed parallel with the two said arms to engage the same, and a valve mounted on the lever to close the outlet port.

5. In a steam trap, a casing, a closure plate 105 removably attached to one side thereof, a valve operatively mounted upon the plate, a coupling including an outlet port forming a valve seat mounted in the plate, and a thermo-loop secured to the plate and connected with the valve for operating the same.

Signed at Bridgeport, in the county of Fairfield and State of Connecticut, this 26th day of April, A. D. 1920.

GEORGE W. COLLIN.
